CARTON AND BLANK FOR FORMING THE SAME

Henry Kondolf, New York, N. Y., assignor to
 Southern Kraft Corporation, New York, N. Y.,
 a corporation of Delaware

Application May 29, 1933, Serial No. 673,539

5 Claims. (Cl. 229—43)

My present invention relates to improvements in shipping containers and more particularly to an improved form of cover for shipping cases adapted primarily for bottled products and the like.

The primary feature of my present invention is to provide, as an element of my shipping unit, a new and improved double cover made from a unitary blank, the inside section thereof being provided with a plurality of openings equal in number to one half the number of bottles in the container or carton, each opening being of a size to receive the necks of two bottles.

Another feature of my present invention is to provide an improved method of constructing a cover of sheet material, the specific material employed constituting one of the many features of my invention. Preferably I make use of a double faced kraft corrugated board, although for certain other purposes I prefer to employ a material consisting of a sheet of wood veneer or similar fibrous material covered with facing sheets. However, it will be readily appreciated that any suitable material may be used.

Other objects and novel features of construction and arrangement of parts comprising the carton or shipping package will appear as the description of my invention proceeds.

Fig. 1 is a developed plan view of sheet material blank from which the cover of the carton is constructed;

Fig. 2 is a perspective view of the completed cover;

Fig. 3 is a sectional elevation through the container, separator, and cover, and with the articles to be held in position within the carton.

According to my invention I have provided a cover for a shipping case which will prevent breakage of the bottles and which will meet all the many requirements of the shipping regulations. This cover is shown in Figs. 1 and 2 and comprises a unitary blank divided into a top cover panel 49, a bottle-holding panel 50, a hinge section 51, by means of the parallel score lines 52. The top cover is provided with a flap 53 defined by score line 54 and is cut away at each end for a purpose to be hereinafter described. The cover panel is also provided with spaced openings 55 and 56, preferably one on each edge of the cover and constituting hand-holds. The openings 56 are formed by a semi-circular cut 57 which permits the folding inwardly of a tongue along the score lines 52 and 54. The bottle-holding panel 50 is provided with openings equal in number to

one-half the number of bottles to be shipped in the cartons and of a diameter to fit snugly around the neck of two bottles. Each opening is formed by a pair of spaced parallel score lines 58, the ends being joined by a semi-circular cut. A cut 59 is located between the score lines. Panel 50 is also provided with a flap 60 similar in form to flap 53.

After the cover has been folded as shown in Fig. 2 it is ready for positioning on the carton. It will be noted that hinge section 51 and flap 60 together form spacing means to maintain the two cover sections separate. Cover flap 53 extends over the outside of the carton wall. As shown in Fig. 3 the cover panel is placed in position the bottles in the nests 36 force the flaps formed by cuts 59 and score lines 60 upwardly. Due to the inherent resiliency of these flaps the bottles are held firmly in spaced relation. To secure the cover permanently in place I make use of staples or other similar securing means 61 which pass through the carton wall, hinge section 51 and tongue 56 on one side of the cover and which extend through flap 53, carton wall, flap 60 and the other tongue 56.

From the above description it will be appreciated that I have provided a new and improved shipping carton or package by means of which bottled goods may be distributed to the consumer at a minimum of expense and which offers many advantages to the manufacturer, bottler, transportation lines, wholesaler, retailer and consumer.

While in the foregoing description and accompanying drawing the invention has been set forth in the particular detailed form which in practice has been found to answer to a satisfactory degree the ends to be attained, it will be understood that these details may be variously changed within the skill of the mechanic, without departing from the limits of the invention; and further, it will be understood that the invention is not limited to any particular form or construction of the parts, except in so far as such limitations are specified in the claims.

What I claim as new is:

1. A blank for forming a cover structure for a carton comprising a top cover panel having a flap formed at one end thereof, a bottle-holding panel hinged thereto at the other end thereof, said bottle-holding panel being provided with openings equal in number to one-half the number of bottles to be shipped in a carton with which the cover is used and of a diameter to fit snugly

around the necks of two bottles, each opening being formed by a pair of spaced parallel score lines having their ends joined by semi-circular cuts, said cuts being joined by a slit located substantially equally distant between the score lines whereby to form a pair of flaps for each opening adapted to resiliently engage the necks of bottles positioned in the carton.

2. A blank for forming a cover structure for a carton comprising a top cover panel having a flap formed at one end thereof, a bottle-holding panel hinged thereto at the other end thereof, said bottle-holding panel being provided with openings equal in number to one-half the number of bottles to be shipped in a carton with which the cover is used and of a diameter to fit snugly around the necks of two bottles, each being provided with a pair of flaps adapted to resiliently engage the necks of bottles positioned in the car-
ton.

3. A blank for forming a cover structure for a carton comprising a top cover panel, a bottle-holding panel hinged thereto at one end thereof, said bottle-holding panel being provided with openings equal in number to one-half the number of bottles to be shipped in a carton with which the cover is used and of a diameter to fit snugly around the necks of two bottles, each opening being formed by a pair of spaced parallel score lines having their ends joined by semi-circular cuts, said cuts being joined by a slit located substantially equally distant between the score lines

whereby to form a pair of flaps for each opening adapted to resiliently engage the necks of bottles positioned in the carton.

4. A blank for forming a cover structure for a carton comprising a top cover panel having a flap formed at one end thereof, a bottle-holding panel hinged thereto at the other end thereof, said bottle-holding panel being provided with openings equal in number to one-half the number of bottles to be shipped in a carton with which the cover is used and of a diameter to fit snugly around the necks of two bottles, said bottle holding panel also being provided with a flap, each opening being formed by a pair of spaced parallel score lines having their ends joined by semi-circular cuts, said cuts being joined by a slit located substantially equally distant between the score lines whereby to form a pair of flaps for each opening adapted to resiliently engage the necks of bottles positioned in the carton.

5. A blank for forming a cover structure for a carton comprising a top cover panel having a flap formed at one end thereof, a bottle-holding panel hinged thereto at the other end thereof and being provided with bottle-receiving openings, a flap secured to the opposite edge of said bottle-holding panel, said cover panel being provided adjacent the edges thereof with a plurality of cut-out portions to facilitate the insertion of staples through the cover and walls of a carton.

HENRY KONDOLF.
